UNITED STATES PATENT OFFICE.

JAMES V. PORTER, OF CONNEAUT, OHIO, ASSIGNOR OF ONE-HALF TO TIMOTHY J. WATSON, OF CONNEAUT, OHIO.

MILK-BOTTLE CONTAINER.

Application filed March 9, 1923. Serial No. 623,996.

To all whom it may concern:

Be it known that I, JAMES V. PORTER, a citizen of the United States, residing at Conneaut, in the county of Ashtabula and 5 State of Ohio, have invented certain new and useful Improvements in Milk-Bottle Containers; and I do hereby declare the following to be a full, clear, and exact description of the invention, such as will enable 10 others skilled in the art to which it appertains to make and use the same, reference being had to the accompanying drawings, and to the letters of reference marked thereon, forming part of this specification.

15 This invention relates to boxes for receiving milk bottles, and the object thereof is to provide a box which will lock itself when the lid is closed after a bottle of milk is placed therein. To accomplish this object I provide 20 a box with a hinged cover which will fall shut when released by the hand, and a vertically movable hook with mechanism, adapted to be actuated by the weight of a bottle, placed in the box, so that it will be engaged 25 by a latch hook on the box cover, but which hook will not co-engage when there is no bottle in the box. These and other features 30 of my invention will be hereinafter fully set forth and pointed out, and are illustrated in the accompanying drawings, in which:

Figure 1 is a front elevation of my improved bottle receiving box, with a portion of the front wall thereof broken away.

35 Figure 2 is a vertical section of the same on the line 2—2 in Fig. 1.

Figure 3 is a fragmentary section on the line 2—2 in Fig. 1 showing the position of the locking mechanism when the box is 40 empty.

In these drawings A indicates the front wall of a box, which may be secured on the side of a house or other suitable support. A' indicates the back, A² and A³ side walls. 45 A⁴ indicates a false bottom, A⁵, indicates the bottom, which is spaced from the false bottom A⁴ and B indicates a cover which is hinged to the back A' by means of hinges b. The front portion b', of the cover B is preferably concaved as shown in the drawings, the end walls of the box being curved to fit said concaved cover, so that when the cover B is raised to a vertical position, the front edge thereof will be forward of the hinges b so 55 that it will fall shut, by reason of its own

weight, when the cover is released by hand.

The interior of the box is preferably divided into compartments by means of a division wall a. While I have shown only two compartments it will be obvious that the 60 box can be made with as many compartments as is desired without departing from the scope of my invention.

Within one of the compartments I place a vertically movable latch hook C which is 65 secured upon a rod C' slidably mounted in a bracket e secured on the inner side of the front A of the box, and extends downwardly through the false bottom A⁴ of the box. In the space between the false bottom A⁴ and the bottom A⁵ of the box are levers D which are pivoted to brackets d secured to the under side of the false bottom A⁴, said levers D having one end of each pivoted to the lower end of the rod C'. Pivoted to the opposite end of each lever D is a post E, which extends upwardly through the false bottom A⁴ into each compartment, so that said posts will be engaged by a bottle F placed therein. The weight of which will operate said levers 70 D to move the rod C' and latch hook C to its uppermost position as shown in Figs. 1 and 2. Upon the under side of the cover B I secure a lock-hook G which is provided with a counter-weight arm g which will 75 cause the lock-hook G to move forward to engage the latch-hook C when the cover B drops down to close the box. The latch-hook C is provided with a stud-post g' by means of which the latch-hook G may be disengaged from the lock-hook. On the outside 80 of the front wall A of the box I secure a bracket H in which is slidably mounted a locking slide, said slide and bracket being provided with openings which coincide 85 when the slide J is in its outermost position as shown in Fig. 2, said coinciding openings being adapted to receive the loop of a padlock, see Fig. 2. The slide J is provided with an arm J' see Figs. 1 and 3, 100 which extends into the box and is adapted to engage the stud-post g' on the latch hook G.

In operation, the box being empty, the latch-hook will be in the position shown in Fig. 3, so that the locking hook will not engage it when the cover B is closed. The slide J is locked in its outermost position as shown in Fig. 2, so that the locking hook G will not be engaged when the cover is closed. The cover B is raised, and a bottle of milk 110

is placed in the box, which pushes the post E downward, thereby operating a lever D to move the latch hook C upward to the position shown in Fig. 2. The cover B is 5 allowed to close and the locking hook engages the latch hook which securely locks the cover. When it is desired to remove the bottle F, the lock K is removed, and the slide J pushed inwardly, which disengages the 10 lock-hook G from the latch-hook C so that the cover B can be raised. The removal of the bottle F allows the latch hook C and C' to move downwardly to the position shown in Fig. 3, so that when the cover B again 15 drops down it will not be locked. The slide J is then pulled outward and the lock K replaced, and the box is ready to receive another bottle.

Having thus fully shown and described the 20 construction and operation of my invention and mechanism suitable for embodying the same I do not desire to be limited to the exact mechanism shown and described as many modifications can be made therein without

departing from the scope of my invention, 25 but what I claim as new and desire to secure by Letters Patent is:

In an apparatus of the class described, a box, a cover therefor hinged thereon, a lower bottom therefor, an inner bottom spaced 30 above the lower bottom so as to form a chamber between said bottoms, a lever pivoted between said bottoms, a vertically slidable post pivoted to one end of said lever and extending upwardly through said inner bottom, a guide bracket secured to the inner face of the front wall of said box, a vertically slidable rod pivoted to said lever and extending upwardly through said inner bottom, and through said guide bracket, a latch-hook on the upper end of said rod, a vertically swinging latch-hook adapted to co-act 35 with the latch-hook on said rod pivoted on said hinged cover, and means to yieldingly maintain said pivoted hook in a forward 40 position.

In testimony whereof I affix my signature.
JAMES V. PORTER.
